(21) Appl. No.: **29/179,254**

CLAIM

(22) Filed: **Apr. 8, 2003**

I claim the ornamental design for a landscaping block with tubular rope lighting groove for straight or curved edging, as shown and described.

(51) LOC (7) Cl. **25-01**

DESCRIPTION

(52) U.S. Cl. **D25/113**

(58) Field of Search D25/112-113,
D25/164; D21/484-486, 493; 405/16, 272,
284; 404/27-31, 34, 41-42, 22-24; 52/574-575,
600, 604, 608, 270; D28/8.1

(56) **References Cited**

FIG. 1 is a perspective view of a landscaping block with tubular rope lighting groove for straight or curved edging showing my new design;

FIG. 2 is a side elevational view thereof;

FIG. 3 is a top plan view thereof, the bottom plan view being identical thereto;

FIG. 4 is an end elevational view thereof;

FIG. 5 is an elevational view of the opposing end thereof;

FIG. 6 is an elevational view of the opposing side thereof; and,

FIG. 7 is a reduced perspective view showing the block in condition of use with like blocks and a rope light shown in broken lines and forming no part of the claimed design.
